TOWEL RACK

Adolph Marchand, Jackson Heights, N. Y.

Application November 26, 1949, Serial No. 6,279

Term of patent 7 years

(Cl. D33—16)

To all whom it may concern:

Be it known that I, Adolph Marchand, a citizen of the United States, residing in Jackson Heights, county of Queens, State of New York, have invented a new, original, and ornamental Design for a Towel Rack, of which the following is a specification, reference being had to the accompanying drawing, forming part thereof:

In the drawing:

Fig. 1 is a perspective view of a towel rack showing my new design; and

Fig. 2 is an enlarged fragmentary perspective view taken from the rear and showing one end of the towel rack in section.

I claim:

The ornamental design for a towel rack, as shown and described.

ADOLPH MARCHAND.
